UNITED STATES PATENT OFFICE

NILS A. WAHLBERG, OF DERRY, PENNSYLVANIA, ASSIGNOR TO WESTINGHOUSE ELECTRIC & MANUFACTURING COMPANY, A CORPORATION OF PENNSYLVANIA

CONDUCTOR CLAMP

Application filed September 13, 1928. Serial No. 305,731.

My invention relates to conductor clamps and particularly to clamps for supporting high-voltage transmission-line conductors or cables.

5 One object of my invention is to provide a device of the above indicated character that shall prevent the imposition of damaging forces of a certain character on surrounding elements, such as a suspension element of the clamp itself, an insulator to which the suspension element is attached and a main supporting tower or a structure.

10 Another object of my invention is to provide a clamp embodying a conductor receiving channel member that shall so embody novel integral side trunnion or supporting portions as to provide a rugged and compact structure that conserves material, reduces the number of clamp parts and has other advantages.

15 A further object of my invention is to provide a clamp that shall be simple and durable in construction, economical to manufacture and effective in its operation.

20 It is usual, in supporting high-voltage transmission-line conductors or cables, to provide clamps having channel members for receiving the conductors.

25 It has been suggested to support such a channel member by trunnions projecting laterally from the channel side walls on axes extending through the longitudinal axis of the conductor for the reception of a pivoted suspension element or yoke.

30 The latter structure, by reason of the positions of the trunnion axes relative to the axis of the conductor, prevents the imposition of certain damaging forces from the conductor and channel member against the suspension element of the clamp and other parts connected to the suspension element.

35 However, by reason of the peculiar position of the trunnions relative to the side walls of the channel, manufacturing difficulties occur in the provision of the trunnions at these positions, it being difficult to drop forge or cast solid cylindrical trunnions on the relatively thin side walls of the channel members.

40 In an endeavor to overcome the above-mentioned objections, it has been proposed to

provide separately formed means, or means constructed independently of the channel member and secured thereto, for supporting the trunnions. This structure is relatively complicated and expensive.

55 It is my aim to overcome all of the above mentioned objections and accordingly, in practicing my invention, I provide a single integral channel member and trunnions that are so formed thereon as to overcome the difficulty of providing solid trunnions and the expense of providing independently-mounted trunnions.

60 Figure 1 of the accompanying drawings is a top plan view of a clamp constructed in accordance with my invention, parts being omitted for clearness,

65 Fig. 2 is a side elevational view of the structure shown in Fig. 1, with certain portions broken away,

70 Fig. 3 is an end elevational view of the device shown in Fig. 1, and

75 Fig. 4 is a sectional view taken substantially along the line IV-IV of Fig. 2.

The device comprises, in general, a conductor-receiving or channel member 2 for supporting a conductor 3, a clamping shoe 4 disposed above the conductor 3 in the channel 2, bolts 5 for clamping the shoe 4 in position and a suspension or supporting member 6.

80 The conductor-receiving member 2 is of a usual channel shape having flared ends 8, for preventing fatigue of the conductor 3, and apertured side bosses 9 for the reception of the bolts 5.

85 The exception to the general shape of such members, as usually formed, resides in laterally projecting side trunnion portions 12.

90 These trunnions may be formed, by casting, drop forging, die-pressing sheet material or other operations, by utilizing material that would ordinarily constitute a portion of the straight side walls 14 of the channel member 2. The trunnions 12 are of substantially half-round channel or U-shape, disposed about the lower ends of openings 15 of substantially U-shape in the sides of the channel member 2.

95 The clamping-shoe member 4 is of a usual type having a grooved under surface 17 sub-

stantially conforming to the shape of the conductor 3, flared end portions 18 and seat portions 19 for positioning the bolts 5.

The bolts 5 may be **U** or **J** bolts that are secured in position by lock washers 20 and nuts 21.

The supporting or suspension yoke 6 is preferably constructed of half portions 24 that are joined by a bolt 25 and include complementary half-socket portions 26 and depending legs 27; the latter having free-end bearing portions 28 for disposition about the trunnion portions 12 of the channel 2.

In operation, since relative movement of the suspension element 6 and the channel member 2 is only through a part of a revolution away from the position indicated in Fig. 2, substantially all of the weight of the conductor and clamp parts remains at the lower bearing surfaces of the portions 28 so that complete cylindrical trunnions are not essential.

In ordinary clamp structures having the axes of such trunnions or similar members disposed any appreciable distance above or below the conductor, damaging forces are imposed against the suspension element 6 in response to vibration or oscillation of the conductor or cable 3.

In the structure constituting my invention, since the axes of the trunnions 12 are disposed in alignment with each other, or on a common axis extending substantially through the longitudinal central axis of the conductor 3, these forces are substantially eliminated.

While I have shown and described a particular form of my invention, changes may be effected therein without departing from the spirit and scope thereof, as set forth in the appended claims.

I claim as my invention:

1. A conductor clamp comprising a conductor-receiving channel member including side walls having openings laterally therethrough and pivot-supporting elements of substantially channel-shape projecting laterally from said walls partially about said openings, said elements being integrally united to said walls and of the material displaced therefrom to provide said openings.

2. A conductor clamp comprising a conductor-receiving channel member having side-wall openings of substantially **U**-shape and pivot-supporting elements of similar shape projecting laterally to said walls adjacent to the closed ends of said openings, said laterally projecting elements being integrally united to said walls and of the material displaced therefrom to provide said openings.

In testimony whereof, I have hereunto subscribed my name this 4th day of September, 1928.
